UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

SMALL BANK.

1,295,768.

Specification of Letters Patent. Patented Feb. 25, 1919.

Application filed December 6, 1916. Serial No. 135,374.

To all whom it may concern:

Be it known that I, ISIDOR J. KUSEL, a citizen of the United States, residing at Chicago, in the county of Cook and State of Illinois, have invented a certain new and useful Improvement in Small Banks, of which the following is a full, clear, concise, and exact description, reference being had to the accompanying drawings, forming a part of this specification.

My invention relates to small banks for coins and other valuables and especially adapted to be kept at home, instead of being carried around in the pocket. Prominent objects of the invention are to provide a simple, practical and efficient construction of bank of this kind; to arrange for the easy reception of the coins and other valuables, but to prevent the improper withdrawal of the same; to arrange for the ready opening of the bank when desired so as to withdraw the contents; to make possible the opening of many banks by an authorized person such, for example, as an officer or employee of a banking institution, but to prevent the opening of any bank by unauthorized persons; to simplify the construction and reduce the cost of manufacture; and to secure the foregoing and other desirable results in a simple and expeditious manner.

In the accompanying drawings Figure 1 is a fragmentary view of a bank of the class specified embodying my present invention;

Fig. 2 is a cross section of the same taken on line 2—2 in Fig. 1 on a reduced scale;

Fig. 3 is a similar section taken on line 3—3 in Fig. 1;

Fig. 4 is a sectional view taken on line 4—4 in Fig. 2, parts of the device being omitted for convenience of illustration;

Fig. 5 is a cross sectional view taken on line 5—5 in Fig. 4; and

Fig. 6 is a sectional view taken on line 6—6 in Fig. 1.

In the accompanying drawings I show a bank conveniently consisting of a base or body member 1 and a top 2 having a flange 3 which fits within the upper portion of the body 1. This top 2 is capable of being bodily separated from the bottom 1 in order to permit the withdrawal of the contents of the bank, but said top is normally locked in engagement with the bottom so as to prevent improper withdrawal of the contents.

The body or bottom 1 is provided with a coin aperture 4, conveniently in the form of a horizontal slot, as shown in Fig. 1. The cover 2 is preferably provided with a device, by which the coins can be received into the bank but which will prevent their leaving it. This trigger or tripping device consists of a tilting platform 6 pivotally mounted at 7 and having one end 8 located near the coin aperture 4, said end being provided with a sloping surface 9, which will ordinarily be struck by the coin when inserted into the aperture 4, so that said platform 6 will be tilted to lower the end 8, whereby the coin may be slid over the top of the portion 9 and upon the top of the platform 6. The weight of the coin thereupon tilts the platform 6 so as to elevate the end 8 and thereby cause or permit the coin to slide down from said platform into the interior of the bank. This platform device serves to close the aperture 4 from the inside, thereby preventing the escape of the coins. The pivot 7 for this platform 6 is conveniently mounted on the side depending walls 10 of a clip member 11 secured to the top 2, a convenient arrangement being to slip the corners of the clip 11 into the groove at the edge of the cover and then to hold the same in position by means of a tongue 12 struck from the body portion 13 of the cover. The clip 11 is also provided with a downwardly extending end portion 14 which serves to some extent as a closure for the space above the platform 6.

This same end of the bank body 1 is preferably provided with an inwardly extending or punched portion 15 adapted to engage a similarly punched in portion 16 on the top 2, whereby this end of the bank may be locked by the engagement of said members.

The other end of the bank is provided with locking mechanism by which the body portion 1 and cover may be normally held in locking engagement. This mechanism comprises a pair of swinging members 17 which are pivotally mounted so as to permit of their being swung in a vertical plane. They are located between the end wall 18 of the bank and a plate 19 secured adjacent to said end wall, preferably by a tubular member 20 which has its ends flanged over so as to make a firm engagement with both the bank wall and the plate 19. This tubular member

serves not only to hold the plate 19 in position but also serves as an aperture by means of which the interior of the bank may be seen, to ascertain how full it is, and said aperture will also serve for the admission of bills, if desired. The upper ends of the swinging members 17 are constructed with hooks 22 and the cover 2 is provided with lugs 23 forming shoulders which can be engaged by said hooks 22, as shown in Figs. 2 and 3, said lugs 23 being conveniently formed by punching the opening in a portion of the rim 3 of said top 2, as shown in Figs. 1, 2 and 3. The swinging movement of said members 17 will cause the engagement and disengagement of the hooks 22 with the lugs 23, and thereby cause the locking and unlocking of that end of the top 2. The lower ends 17^a of the members 17 are separated slightly so as to permit the insertion of a key 25 between the same, as shown in Figs. 2, 3 and 5. This key preferably has an enlarged or projecting portion 26, so that when turned said projecting portion will act upon the lower ends or legs 17^a and thereby cause the same to separate from one another and thereby retract the hooks 22 to move them into unlocking position. For the accommodation of the key 25 the portion 18 of the bank wall and the plate 19 are provided with apertures 27 and 28 respectively, as shown in Figs. 4 and 5. In order to hold the swinging members 17 normally in locking position a spring is provided, the same conveniently consisting of a single piece of wire 29, Fig. 4, extended up around the tubular member 20 and having its lower ends bent to form lateral engaging portions 30 which pass through apertures in the lower ends of the legs 17^a. This spring tends normally to draw the legs 17^a together and so hold the hooks 22 in an outward or locking position. The key 25 spreads these legs and operates against said spring to unlock the device.

All of the parts herein can be stamped from sheet metal, consequently the device can be made cheaply and rapidly in great numbers.

Changes and modifications may be made without departing from the spirit of the invention.

What I claim is:

1. A bank having a locking mechanism consisting of a pair of swinging members pivotally mounted at a common point, the upper ends of said members being provided with engaging hooks and the lower ends being separated and located in position to be acted upon by a key, the pivotal support of said swinging members being a tubular member forming an aperture in the side wall of the bank.

2. A bank having a locking mechanism consisting of a pair of swinging members

pivotaly mounted at a common point, the upper ends of said members being provided with engaging hooks and the lower ends being separated and located in position to be acted upon by a key, and a spring tending to hold said swinging members normally with their upper ends in locking position, said swinging members being pivotally mounted on a tubular member serving as a bill aperture for the bank.

3. The combination with the base or bottom of a bank, a plate secured in position adjacent a portion of one end of said base or bottom, a tubular device secured to said wall portion and said plate to hold the latter in position, a pair of swinging members mounted on said tubular member and located between said wall portion and said plate, the upper ends of said swinging members being provided with engaging hooks and the lower ends being separated, the wall portion and plate being provided with apertures in a line between said members for the reception of a key, a spring acting upon the lower ends of said members to hold the same normally close together, and a top for said base member, said top being provided with lugs adapted to engage said engaging hooks.

4. In a bank having a coin aperture, a swinging platform located near said aperture and in substantially horizontal alinement with the same, said platform having its end nearest said aperture provided with an inclined surface which is adapted to substantially close said aperture when said platform is in substantially horizontal position, said platform being pivotally mounted to permit of its being tilted by a coin entering said aperture and striking said inclined surface of said platform, and also to permit said platform to be swung by the weight of the coin on the end farthest from the aperture so as to cause said inclined surface to again come into position substantially in front of said aperture to prevent the escape of coins.

5. A bank having an aperture for bills and a tubular member fitted to said aperture to form an inlet for the bills, and locking mechanism mounted upon said tubular member.

6. A bank having an aperture for bills and a tubular member fitted to said aperture to form an inlet for the bills, and locking mechanism mounted upon said tubular member, said locking mechanism comprising swinging locking members pivoted on said tubular member and provided with means whereby they may lock and unlock the bank, and also with means whereby they may be actuated by a key.

7. A bank having an aperture for bills and a tubular member fitted to said aperture to form an inlet for the bills, and locking mechanism mounted upon said tubular mem-

ber, said locking mechanism comprising swinging locking members pivoted on said tubular member and provided with means whereby they may lock and unlock the bank, 5 and also with means whereby they may be actuated by a key, and a plate mounted within the bank and serving as a support for the inner end of said tubular member, and also provided with an aperture to receive the

inner end of the key and hold the same in 10 position.

In witness whereof, I hereunto subscribe my name this 15th day of November, A. D., 1916.

ISIDOR J. KUSEL.
